US0D1097215S

(12) **United States Design Patent** (10) **Patent No.:** **US D1,097,215 S**
(45) **Date of Patent:** **** Oct. 7, 2025**

(54) **BASE FOR A SAFETY RAIL**

(71) Applicant: **DELTA PRÉVENTION INC.**,
Brossard (CA)

(72) Inventors: **Daniel Wu**, Montreal (CA); **Anthony Caron**, Saint-Amable (CA); **Pierre-Luc Lussier**, Boucherville (CA)

(73) Assignee: **DELTA PRÉVENTION INC.**,
Brossard (CA)

(**) Term: **15 Years**

(21) Appl. No.: **29/920,852**

(22) Filed: **Dec. 13, 2023**

(30) **Foreign Application Priority Data**

Jul. 17, 2023 (CA) ..... CA 222877

(51) **LOC (15) Cl.** **25-01**

(52) **U.S. Cl.**

USPC **D25/133**

(57) **CLAIM**

The ornamental design for a base for a safety rail, as shown and described.

DESCRIPTION

FIG. 1 is a perspective top view of the base for a safety rail;
FIG. 2 is a top view of the base for a safety rail of FIG. 1;
FIG. 3 is a first side view of the base for a safety rail of FIG. 1;

FIG. 4 is a second side view of the base for a safety rail of FIG. 1;

FIG. 5 is a bottom view of the base for a safety rail of FIG. 1; and,

FIG. 6 is a perspective bottom view of the base for a safety rail of FIG. 1.

The broken lines illustrate portions of the base for a safety rail that form no part of the claimed design.

1 Claim, 4 Drawing Sheets
